UNITED STATES PATENT OFFICE.

HARRY A. LYMAN, OF MERIDEN, CONNECTICUT.

DESIGN FOR AN ELECTRIC SIGN.

Application filed March 29, 1924. Serial No. 9,107. Term of patent 7 years.

To all whom it may concern:

Be it known that I, HARRY A. LYMAN, a citizen of the United States, residing at Meriden, in the county of New Haven and State of Connecticut, have invented a new, original, and ornamental Design for Electric Signs, of which the following is a specification, reference being had to the accompanying drawings, forming part thereof.

Figure 1 is a front perspective view of an electric sign showing my new design.

Figure 2 is a rear perspective view of the same.

I claim:

The ornamental design for an electric sign as shown.

HARRY A. LYMAN.
